UNITED STATES PATENT OFFICE.

CAMILLA M. HIRSCH, OF NEW ULM, MINNESOTA.

BAG-HOLDER.

SPECIFICATION forming part of Letters Patent No. 658,848, dated October 2, 1900.

Application filed June 25, 1900. Serial No. 21,450. (No model.)

To all whom it may concern:

Be it known that I, CAMILLA M. HIRSCH, a citizen of the United States, residing at New Ulm, in the county of Brown and State of Minnesota, have invented certain new and useful Improvements in Bag-Holders; and I do hereby declare that the following is a full, clear, and exact description of the same, reference being had to the annexed drawings, making 5 a part of this specification, and to the letters of reference marked thereon.

The present invention has reference to bag-holders, and has for its object to provide such a device that will be simple in construction 15 and effective in holding the mouth of the bag open or extended and retaining the bag in an upright position to facilitate filling the same; and it consists in a bag-holder constructed substantially as shown in the drawings and 20 hereinafter described and claimed.

Figure 1 of the drawings is a perspective view showing the bag-holder and bag suspended over a suitable vessel, the vessel being shown in dotted lines and the legs or supports in two positions in full and dotted lines. Fig. 2 is a detail side elevation, on an enlarged scale, showing the manner of pivotally-connecting or hinging the upper end of the leg to the frame of the holder.

30 In the accompanying drawings, A represents a suitable frame, consisting of a band of circular or other form and of metal or other suitable material, as found best adapted to the purpose. This frame A has external means for 35 attaching a bag thereto, consisting of headed pins *a* or spurs *b*, as shown in Fig. 2 of the drawings, or any other desirable means may be employed for temporarily securing the bag to the frame while being filled.

40 In Fig. 1 of the drawings the bag B is shown as provided with loops or rings *c* for engaging the headed pins *a*; but this is not necessary where the spurs *b* are used, as the fabric of the bag may be engaged by hooking it 45 onto the spurs, which will serve the same purpose and admit of the bag being conveniently removed when required.

The legs or supports C are pivoted or hinged to the frame A, their upper ends bent at right 50 angles to form a shank *d* to engage an eye-plate *e* and the extremity of the shank bent

at a right angle, as shown at *f*, to prevent the shank from disengaging itself from the plate and also acting as stops for the legs or supports.

55 The legs or supports C have curved feet *g*, the curved ends of the feet being of such shape as to fit over the convex or rounded edge or rim of the fruit-jar or other vessel. The eye-plates *e* are of sufficient width to provide a 60 long bearing for the shank *d* of the leg or support, whereby its pivotal connection with the frame A is materially strengthened. As will be noticed, the eye-plates are secured to the band at a point above the plane of the means 65 employed for attaching the bag to said band, so that the pivotal connection of the supports or legs therewith will not interfere with the removal of the bag from its fastenings and also admit of the bag being readily secured 70 in place.

The holder as above described is adapted for all classes of bags of whatever material and may be made of various sizes to adapt them to the use for which the holder is intended, 75 70 the hinging or pivoting of the legs or supports enabling the device to be used on preserve-jars or other vessels having various-size openings.

Having now fully described my invention, 80 what I claim as new, and desire to secure by Letters Patent, is—

A bag-holder, comprising a suitable band with external means for attaching a bag thereto, legs or supports having feet at their lower 85 ends which are curved as shown to fit over the convex or rounded edge or rim of a fruit-jar or other vessel, and the upper ends of the legs or supports having right-angle shanks with their extremities extending at right angles to the shanks to secure them in place, and eye-plates for pivotally connecting the shanks to the band at a point above the plane 90 of the means for attaching the bag, substantially as and for the purpose set forth. 95

In testimony that I claim the above I have hereunto subscribed my name in the presence of two witnesses.

CAMILLA M. HIRSCH.
